UNITED STATES PATENT OFFICE.

WILLIAM J. ACKERMAN, OF GRAND RAPIDS, MICHIGAN.

BED-SLAT FASTENER.

SPECIFICATION forming part of Letters Patent No. 340,651, dated April 27, 1886.

Application filed February 23, 1886. Serial No. 192,910. (No model.)

To all whom it may concern:

Be it known that I, WILLIAM J. ACKERMAN, a citizen of the United States, residing at Grand Rapids, in the county of Kent and State 5 of Michigan, have invented certain new and useful Improvements in Fastenings for Bed-Slats; and I do declare the following to be a full, clear, and exact description of the invention, such as will enable others skilled in 10 the art to which it appertains to make and use the same, reference being had to the accompanying drawings, and to the letters and figures of reference marked thereon, which form a part of this specification.

15 Figure 1 is a perspective view of side rail, showing slat-plate. Fig. 2 is a perspective view of portion of slat and of my fastening. Fig. 3 is a top view of slat and rail when fastened together. Fig. 4 is a sectional view 20 on the line $x-x$ of Fig. 3.

Similar letters refer to similar parts.

The object of my invention is to furnish a fastening adapted to hold together the side rails of a bedstead and to prevent any spreading thereof.

25 I describe my invention as follows: Upon the under side of and near each end of a bed-slat, B, I fasten, by means of the screw f , the metal disk D, said screw being countersunk 30 therein and permitting a revolving motion of said disk, which is provided with a projecting semicircular lug, c , extending about one-third

its outer circumference, having the flange d . Said disk is also provided with the finger-post e , by which the disk is turned. Upon 35 the side rail A is fastened the plate C, having the inward-projecting flange a and the slot b , the side rail being cut away behind said plate to permit the entrance of the lug c . It will be seen that, the slat being placed in position 40 upon the side rail, the lug c may be thrown around in the slot b , the flange d passing under the flange a , forming a lock.

Having thus described my invention, what I claim, and desire to secure by Letters Patent 4. of the United States, is—

1. In a bed-slat fastening, the disk D, turning on the countersunk screw f , and having a semicircular lug, c , with flange d thereon, and the finger-post e , in combination with a lock- 5 ing side plate, as shown and described.

2. In a bed-slat fastening, the disk D, turning on the countersunk screw f , and having a semicircular lug, c , with flange d thereon, having also the finger-post e , in combination with 5 the side plate, C, having the slot b and flange a , substantially as shown and described.

In testimony whereof I affix my signature in presence of two witnesses.

WM. J. ACKERMAN.
